INVENTOR:

Frank B. Cook.

UNITED STATES PATENT OFFICE.

FRANK B. COOK, OF CHICAGO, ILLINOIS.

LIGHTNING-ARRESTER.

No. 838,304.

Specification of Letters Patent.

Patented Dec. 11, 1906.

Application filed May 9, 1906. Serial No. 316,028.

To all whom it may concern:

Be it known that I, FRANK B. COOK, a citizen of the United States of America, residing at Chicago, in the county of Cook and State 5 of Illinois, have invented a new and useful invention entitled "Lightning-Arrester," of which the following is a specification, reference being had to the accompanying drawings, illustrating same.

My invention relates to high-potential electricity-arresters, and more particularly to lightning-arresters.

The principal objects of my invention are to provide a self-cleaning lightning-arrester 15 and a lightning-arrester which will automatically short-circuit itself upon the continuance of an arc therethrough.

In the lightning-arresters generally in use comprising the usual carbon blocks and interposed mica dielectric the mica holds the carbons apart during the continuance of an arc through the arrester, and thereby allows the carbons to become red-hot and the arc to continue until the carbon surfaces are actually burned together. Then, again, the mica dielectric provided with the usual holes therein provides a construction which holds carbon dust or particles of carbon between the blocks, and thereby forms a short-circuit 25 through the arrester when it is not desired.

With such an arrester the carbons have to be taken apart and cleaned after each ordinary discharge through the arrester.

In my present invention I preferably employ the usual carbon blocks for the electrodes of the arrester; but instead of the mica dielectric I employ a dielectric of a material which will become softened under a continued arc through the arrester, and thereby 35 allow the carbon blocks to be pressed together and short-circuited, thus stopping the arc. Such a dielectric is very desirable in certain cases, especially in telephone systems exposed to electric light or street-car currents of reasonably high voltages. Then I 40 cut away one side portion of the dielectric to near the center thereof, so as to allow the particles of carbon which may be broken off during a discharge through the arrester to fall 45 from between the carbons, and thereby keep the air-space between the blocks free from obstructions and the lightning-arrester free from

a short-circuit after a discharge has passed therethrough.

Referring to the accompanying drawings, 55 Figure 1 is a perspective view of the lightning-arrester of the invention, and Fig. 2 is a side elevation of the dielectric of the invention.

The dielectric 2 is placed between the carbon blocks 1 1, as shown in Fig. 1. One side 60 portion of the dielectric 2 is cut away, preferably as shown at 3. This cut-away portion 2 allows the particles of carbon to fall from between the blocks 1 1 when the arrester shown in Fig. 1 is placed in a horizontal 65 position. For this dielectric 2 I preferably use a thin sheet of celluloid. When an arc continues through the arrester for a short length of time, the heat of the arc softens or melts the celluloid dielectric 2, and thereby 70 allows same to ooze out from between the blocks 1 1 due to the ordinary spring-pressure on the blocks 1 1, and the latter to make electrical connection with each other and establish a short-circuit therebetween, which stops 75 the continuance of the arc. If the arc is of short duration, it will simply pass from one block to the other through the cut-away portion 3 of the dielectric without melting or softening the latter. The lightning-arrester 80 shown in Fig. 1 may be held in place in the circuit in any well-known manner.

Having thus described my invention, what I claim as new, and desire to secure by Letters Patent, is—

85

1. In a lightning-arrester of the character described, suitable electrodes held adjacent to each other, and a thin dielectric of softenable material interposed between the electrodes and having one side portion thereof 90 cut away approximately to the center.

2. In a lightning-arrester of the character described, suitable electrodes held adjacent to each other, and a celluloid dielectric interposed between the electrodes and having a 95 side portion thereof cut away approximately to the center.

3. In a lightning-arrester of the character described, suitable electrodes held adjacent to each other, and a U-shaped celluloid dielectric interposed between the electrodes.

4. In a lightning-arrester of the character described, suitable electrodes held adjacent to each other, and a U-shaped dielectric of

softenable material interposed between the electrodes.

5. In a lightning-arrester of the character described, rectangular carbon blocks suitably held in a horizontal position and adjacent to each other, and a U-shaped dielectric of heat-susceptible material interposed between the carbon blocks.

As inventor of the foregoing I hereunto subscribe my name, in the presence of two ~~re~~ subscribing witnesses, this 7th day of May, 1906.

FRANK B. COOK.
